[57] CLAIM

The ornamental design for a hinged lamp, as shown and described.

DESCRIPTION

FIG. 1 is a top, front, right side perspective view of a hinged lamp showing my new design;

FIG. 2 is a top, front, perspective view thereof in an alternate position;

FIG. 3 is a right side elevational view thereof in an alternate position, the left side being a mirror image;

FIG. 4 is a top plan view thereof;

FIG. 5 is a bottom plan view thereof;

FIG. 6 is a front elevational view thereof; and

FIG. 7 is a rear perspective view thereof.
